United States Patent Office

Des. 206,244

Patented Nov. 15, 1966

206,244

LIQUID CONTAINER

William H. Coy, Lower Burrell, Pa., assignor to Aluminum Company of America, Pittsburgh, Pa., a corporation of Pennsylvania

Filed Mar. 25, 1965, Ser. No. 84,439

Term of patent 14 years

(Cl. D58—17)

FIG. 1 is a top plan view of a liquid container in accordance with my invention;

FIG. 2 is a side elevation thereof partially broken away and in section;

FIG. 3 is another side elevation thereof rotated clockwise at an angle of 90 degrees; and

FIG. 4 is a perspective view thereof.

I claim:

The ornamental design for a liquid container, substantially as shown.
